GUSTAV N. MADSEN, OF MINNEAPOLIS, MINNESOTA, ASSIGNEE OF ONE-THIRD TO
CARL R. LINDE AND ONE-THIRD TO ERIC B. GUSTAFSON, BOTH OF MINNEAPOLIS,
MINNESOTA.

ELECTRIC WATER HEATER.

Application filed September 30, 1925. Serial No. 59,631.

- One object of my invention is to provide a heater, such that hot water may be supplied from individual taps throughout the system with a minimum amount of pipe.
- Another object is to provide an improved form of instantaneous water heater wherein the water to be heated traverses an extreme length of surface.
- Another object is to provide in a water heater, means for actuating the heater whenever the tap is opened so the water flowing therefrom will be heated as it flows.
- With these and incidental objects in view, the invention consists of certain novel features of construction and combination of parts, the essential elements of which are hereinafter described with reference to the drawings, which accompany and form a part of this specification:
- 20 In the drawings, Figure 1 is a side elevation of my improved form of heater removed from the cabinet. Figure 2 is an enlarged sectional detail of a fragment of one of the heating elements and pipes. Figure 3 is a side elevation of a tap showing one way in which the current flowing thru the heater can be controlled. Figure 4 is a front view of the controlling switch and Figure 5 is a section taken on the line 5—5, Figure 3.
- 25 Looking now at Figures 1 and 2, the cold water may be brought in at either of the points 20 or 21, as it passes thru the heater under pressure and does not depend upon thermal circulation.
- 30 The heating element 22 is positioned within the tube or pipe 23 from which it is insulated and this pipe 23 screws into the head 24, the connections of the heating element being brought out by suitable wires at 25, into the outlet box 26.
- 35 The outer pipe 27 is screwed on to the head 24, thus providing a space between the pipes 23 and 27 thru which the water may circulate and as the heating element in the pipe 23 is entirely surrounded by water all of the heat confined therein is absorbed by the water.
- 40 The nipples 28, preferably with right and left hand threads connect the various pipes 27, as shown in Figure 1, so the water circulates thru the entire series of pipes and it is evident that if the water enters at 21 for instance, in passing thru the length of the first pipe, it will be slightly warmed and in
- passing down the length of the second pipe, so that by the time it reaches the outlet at 20, the water will be as hot as desired and the heater is so designed that by allowing the water to travel over a long length of heated inner pipe 23, the water may be raised to the desired temperature as quickly as it flows with a minimum amount of electrical energy.
- 45 The outlet box 26 provides convenient means for joining the wires from the various elements together and they are brought out at the last terminal box 29 where suitable connection may be made to the service box thru the switch which will not be described.
- 50 Looking at Figure 3, it will be seen that the water which flows from the heater to any one of the hot water taps, passes thru the housing 30.
- 55 Looking at Figure 5, it will be seen that the water entering this housing at 31 and passing out at 32 will tend to rotate the water wheel 33 in a counter-clockwise direction.
- 60 Looking now at Figure 4, it will be seen that the rotation of the shaft 34 on which the water wheel is suitably fastened, will swing the arm 35 in a counter-clockwise direction against the tension of the spring 36, thereby closing the contact 37, which is the control contact for the current supplied to the heater.
- 65 It is evident therefore, that whenever any one of the hot water taps is opened the individual control switch will be closed and the heater associated with that tap will be energized and the water passing therethru and out thru the tap will be heated as fast as it flows.
- 70 I am aware that there have been many forms of electrical water heaters, but I believe that I am the first to have devised a system wherein a single cold water main serves the purpose of providing hot and cold water throughout the entire building and I believe that I am also the first to have provided a heater in such form that the water passes over a plurality of heating elements in a series so that while the water leaving the last element is of very high temperature, no one of the individual elements is required to raise the temperature of the water to any great extent while the water is passing over that in-

dividual element, but the action is accumulative so that the water entering cold finally leaves the heater at a desired temperature.

While I have described my invention and illustrated it in one particular design, I do not wish it understood that I limit myself to this construction, as it is evident that the application of the invention may be varied in many ways within the scope of the following claim.

Claim:

In an electrical water heater, the combination of a plurality of heating units, each comprising an electrical heating element, a pipe surrounding said element and insulated therefrom, a second pipe concentric with said first named pipe but spaced therefrom, a

head carrying both of said pipes, a closure for the free end of the outer of said pipes, means for bringing electrical connections from said element to the exterior of said head, individual outlet boxes for each of said units with conduits therebetween to facilitate the inter-connection of said elements, pipe connections between the outer pipes of adjacent units, an inlet for the first of said units leading to the interior of the outer pipe and of an outlet for the last of said units leading to the interior of the outer pipe thereof, so water may be passed thru all of said outer pipes in series and heated by the elements in said individual pipes.

GUSTAV N. MADSEN.
